UNITED STATES PATENT OFFICE.

WARREN P. SEEM, OF ALTOONA, PENNSYLVANIA.

COHESION-MACHINE.

1,300,494.

Specification of Letters Patent. Patented Apr. 15, 1919.

Application filed January 2, 1918. Serial No. 210,102.

To all whom it may concern:

Be it known that I, WARREN P. SEEM, a citizen of the United States, residing at Altoona, in the county of Blair and State of Pennsylvania, have invented a new and useful Cohesion-Machine, of which the following is a specification.

By way of explanation it may be stated that the quality of a silk thread depends upon the strength with which its constituent fibers adhere together and resist an attempt to separate them transversely. This property has been denominated "cohesion" by Adolph Rosenzweig of Milan, and its importance in determining the quality of a silk thread is recognized. The method of testing resorted to commonly is to separate the fibers of the thread between the thumb and forefinger, noting such results as this crude procedure may make manifest, the personal equation rendering the thumb and forefinger test, at best, no more than a means for arriving at approximate results, which, although better than nothing, are not capable of tabulation and comparison when secured by the efforts of different operators, or even by the efforts of the same operator, working at different times or under different conditions. The sericin or gum or raw silk not only possesses various degrees of adhesiveness, but, also, frequently contains minute particles of foreign matter, such as sand or limestone, which roughens the sericin to such an extent that conclusive results as to cohesion cannot be attained by a mere friction test.

In view of the foregoing, it is the object of this invention to provide a simple but efficient machine whereby cohesion tests on silk threads may be carried out readily, and whereby the results of the tests will be of such a conclusive and uniform nature that they may be compared, thereby producing a standard for cohesion tests.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings:

Figure 1 shows in side elevation, a ma-

chine embodying one form of the present invention;

Fig. 2 is a top plan of the more important parts of the structure, the thread carrier 60 being swung backwardly, so that the lower face thereof is shown;

Fig. 3 is a longitudinal section disclosing the parts delineated in Fig. 2, the line —3—3 in Fig. 2 denoting the cutting plane 65 in which Fig. 3 is taken;

Fig. 4 is a cross section taken approximately on the line 4—4 of Fig. 1; and

Fig. 5 is a cross section taken approximately on the line 5—5 of Fig. 2, a portion 70 of the supporting table appearing as an added detail.

In carrying out the invention there is provided a base 1 which may be in the form of a plate provided adjacent one end with a longitudinal slot 2. Guides 3 are secured to the base 1 on opposite sides of the slot 2. A carriage 4 is mounted to reciprocate on the base 1 and is held thereto for right line movement by means of the guides 3. Oppositely disposed standards 5 and 6 are erected upon the carriage 4. A bearing screw 7 is threaded in the standard 5, a bearing screw 8 being threaded in the standard 6. The standard 6 is divided at its upper end to form compressible jaws 9 adjustably connected by means of a binding screw 10. A pressure member is embodied in the invention, the pressure member preferably being in the form of a roller 11 having tapered ends 12 journaled in the bearing screws 7 and 8. The bearing screw 8 may be advanced and retracted, so as to vary the pressure exerted on the roller 11, and, consequently, to regulate and adjust the freedom with which the roller rotates, as will be made manifest hereinafter. The binding screw 10 may be manipulated to cause the jaws 9 of the standard 10 to grip the bearing screw 8, and in this way the bearing screw may be held in any position so far as its binding effect on the shaft 11 is concerned.

Standards 14 are secured to the base 1 near to the rear end thereof, and in the standards a shaft 15 is mounted to rock. An arm 16, constituting a part of the thread carrier, is secured to the shaft 15 for swinging movement in a vertical plane. A rest 17 is attached to the base 1 and supports the arm 16 when the latter is swung back into the inoperative position shown in Fig. 3. A weight 18 is attached to the free end of the

arm 16 and may be held in place by a securing element 19 engaged with one end of a clip 20, of arched form, located below the arm 16 when the latter is in the working position shown in Fig. 1. A screw 21, threaded into the arm 16, engages the clip 20 and regulates the pressure with which the inner end of the clip coats with the arm 16. The numeral 22 denotes a clip, similar 10 to the clip 20, and controlled by a screw 24 threaded into the arm 16, the outer end of the clip being secured as indicated at 23 to the arm. A counter 25 is secured to the upper surface of the arm 16, between the clips 20 and 22 and includes a depending lever 26 extended into the path of the roller 11. The counter 25 may be of any desired kind, the well known Veeder device being employed if desired. The numeral 27 denotes 20 a thread holder which, together with the arm 16, forms a thread carrier. The thread holder 27 may be in the form of a flexible or resilient card, about which silk threads 28 are wound in any desired number of convolutions, a fixed number preferably being determined upon, and this number being retained in all tests for the sake of uniformity. The threads 28 are spaced from each other and are held in spaced relation by pasting 30 them with adhesive strips, at their ends, to the card or holder 27. After the threads 28 have been mounted on the holder 27 in the manner above alluded to, the holder is placed against the working side of the arm 35 16 and is retained by the clips 20 and 22, the screws 21 and 24 being tightened up so as to compress the clips firmly on the holder and to prevent the holder from shifting.

In practical operation, the arm 16 is 40 swung over from the position of Fig. 3 to the position of Fig. 1, the threads 28 then resting on the roller 11. The carriage 4 is reciprocated between the guides 3, the roller 11 turning in contact with the threads 28, 45 and the threads being pressed against the roller by the action of the weight 18. At each stroke of the carriage 4, the counter 25 is actuated by means of the lever 26 which coats with the roller 11.

50 In order to take readings, the arm 16 is raised and swung back into the position of Fig. 3, the arm being supported on the rest 17. The holder 27 is removed from the clips 20 and 22 and is flexed slightly so as to slacken the threads 28, the threads being raised by means of a spatula or like tool. The threads are examined preferably at the 55 end of every fifty strokes made by the carriage 4, the number of strokes being read off the counter 25. These examinations are continued until all of the threads have been opened throughout the full length of the stroke, by the action of the roller 11. The total number of strokes is read off the 60 65 counter 25 and this forms the unit of cohe-

sion, the process consisting, essentially, in subjecting a fixed number of threads, under a fixed pressure, to a sufficiently great number of strokes to produce an opening of all of the threads. The roller 11 preferably is 70 inclined at an angle of about $2\frac{1}{2}$ degrees to the horizontal so as to approximate the result produced when a silk thread is rubbed between the forefinger and thumb of the human hand. This inclination of the roller 75 11 is indicated in Fig. 4.

Any desired means may be provided for imparting a reciprocating movement to the carriage 4. An efficient means is shown in the drawings for reciprocating the carriage, 80 but I do not bind myself in this respect. As disclosed, the base 1 is attached to a table 24 carried by side frames 30 between which a footboard 31 extends. An upright 32 connects the footboard 31 with the table 85 29. An electric motor 32 is mounted on the board 31 and is controlled by a foot switch 33, the motor including a pulley 34 around which is trained a belt 35 engaged with a wheel 36 journaled on the upright 90 32. A pinion 37 rotates with the wheel 36 and meshes into a gear wheel 38 supported for rotation on the upright 32. A pitman 39 is pivoted to the gear wheel 38 and is pivoted to one end of a rock arm 40, the 95 other end of which is secured to a shaft 41 journaled in bearings 42 carried by the side frames 30. An upstanding arm 43 is attached to the shaft 41, the parts 43, 41 and 40 constituting in effect, a bell crank. One 100 end of a link 44 is pivoted to the arm 43, the other end of the link being pivoted to a depending projection 45 attached to the carriage 4 and movable in the slot 2 of the base 1 and in a registering slot 46 fashioned in the table 29.

When the motor 32 is operated, the pinion 37 is driven by means of the wheel 36, the belt 35 and the pulley 34. The pinion 37 rotates the gear wheel 38, the shaft 41 is 110 rocked by means of the pitman 39 and the arm 40, a reciprocating movement being imparted to the carriage 4, through the instrumentality of the arm 43 on the shaft 41, the link 44, and the projection 45 on the carriage.

Having thus described the invention, what is claimed is:

1. A machine for determining the cohesion of silk threads, comprising a thread carrier; a pressure member adapted to roll in contact with the thread on the carrier and pressing the thread against the carrier; means for mounting the pressure member for rotation; and means for producing relative translatory movement between the pressure member and the carrier.

2. A machine for determining the cohesion of silk threads, comprising a thread carrier; a pressure member coöperating with 130

the carrier; means for mounting the pressure member for rotation; and means for producing relative movement between the pressure member and the carrier.

- 5 3. A machine for determining the cohesion of silk threads, comprising a thread carrier; a carriage mounted to reciprocate with respect to the thread carrier; a roller journaled on the carriage and coöperating 10 with the thread carrier; and means for moving the carriage with respect to the thread carrier.

4. A machine for determining the cohesion of silk threads, comprising a base; an 15 arm pivoted to the base; thread holding means carried by the arm; a carriage mounted to reciprocate on the base; a roller journaled on the carriage and coacting with the arm; and means for reciprocating the carriage.

5. A machine for determining the cohesion of silk threads, comprising a base; an arm pivoted to the base; a carriage mounted to reciprocate on the base; means for reciprocating the carriage; a roller journaled on the carriage and coacting with the arm; and a counter carried by the arm; the counter comprising a part extended into the path of the roller.

- 25 30 6. A machine for determining the cohesion of silk threads, comprising a base; an arm pivoted to the base; thread holding means carried by the arm; a pressure member mounted to reciprocate on the base and

coacting with the arm; means for reciprocating the pressure member; and a counter on the arm, the counter comprising a part extended into the path of the pressure member.

7. A machine for determining the cohesion of silk threads, comprising a base; an arm pivoted at one end to the base; a weight on the other end of the arm; a carriage mounted to reciprocate on the base; a roller journaled on the carriage and coacting with the arm; thread holding means carried by the arm and disposed on opposite sides of the roller; and a counter mounted on the arm and including a part extended into the path of the roller.

8. A machine for determining the cohesion of silk threads, comprising a support; a carriage mounted to reciprocate on the support; a roller journaled on the carriage; a thread carrier pivoted to the support and resting on the roller; a motor on the support and under the control of an operator; and means for connecting the motor with the carriage to secure a reciprocation of the latter.

In testimony that I claim the foregoing as my own, I have hereto affixed my signature in the presence of two witnesses.

WARREN P. SEEM.
